Specification for Design.

Patented July 18, 1922.

Application filed October 22, 1921. Serial No. 509,727. Term of patent 7 years.

To all whom it may concern:

Be it known that I, FREDERICK ROETTGES, a citizen of the German Republic, residing at Stamford, in the county of Fairfield and State of Connecticut, have invented a new, original, and ornamental Design for a Pedestal for Lighting Fixtures, of which the following is a specification, reference being had to the accompanying drawing, forming part thereof.

The figure is a perspective view of a pedestal for lighting fixtures, showing my new design.

I claim—

The ornamental design for a pedestal for lighting fixtures, as shown.

FREDERICK ROETTGES.
